UNITED STATES PATENT OFFICE.

MATHEW WOODS, OF CAPE ELIZABETH, MAINE.

IMPROVEMENT IN CAR-COUPINGS.

Specification forming part of Letters Patent No. **150,453**, dated May 5, 1874; application filed April 9, 1874.

To all whom it may concern:

Be it known that I, MATHEW WOODS, of Cape Elizabeth, county of Cumberland and State of Maine, have invented a new and useful Improved Car-Coupling; and I do hereby declare the following to be a full, clear, and exact description thereof, that will enable others skilled in the art to which it appertains to make and use the same, reference being made to the accompanying drawing forming part of this specification, in which—

Figure 1 is a side elevation; Fig. 2, a vertical longitudinal section.

Same letters show like parts.

The object of my invention is to produce an improved car-coupling, one that will possess all the advantages of the ordinary link-and-pin coupling in common use, and in addition will be automatic in its action. Its construction is simple, and may be thus described:

a represents the draw-head, having its mouth or entrance *b* made somewhat flaring, in order to facilitate the entrance of the link of an approaching draw-head. In the rear part of the hollow of the draw-head *a* are the recesses *c* *c'*, the purposes of which will be hereinafter described. Through the lower part of the draw-head passes horizontally the rod or bar *d*. To this rod or bar *d*, on each side of the draw-head, as shown in the drawing, are firmly attached, eccentrically, the circular plates or disks *e*. On the center of the rod *d*, and firmly attached thereto, is the vertical arm or lever *f*. This lever rests directly, or rather is held by the operation of the disks *e*, before described, under the pin-hole in the top of the draw-head. *g* shows a slot back of the hollow of the draw-head, in which the arm or lever *f* plays when thrown backward by the entrance of the link.

Having thus given the construction of my invention, I will now describe its operation: The lever *f*, by reason of the eccentrically-placed disks *e*, rests, as before specified, directly under the pin-hole in the top side of the

draw-head. The pin *h* is then placed in the pin-hole, and is held elevated by reason of its resting upon the upper end of the vertical arm *f*. The link *i*, entering the draw-head *a*, strikes this vertical arm, and forces it backward and out from under the pin *h*. This operation allows the pin to drop, and completes the operation of the coupling. To facilitate the ready entrance of the link to an approaching draw-head, I have devised the recesses *c* *c'*, before mentioned. When the link enters the draw-head, and forces the lever *f* backwardly, it (the link) passes into the recess *c*, and is thus held in a horizontal position. To aid its entrance to a draw-head which is lower than the one in which the link is held, the said link should be placed in the recess *c'*. This, it will be apparent, will allow the outer end of the link to rest in a lower plane than its inner end, and will permit it to enter a draw-head lower than that in which it is held. It is obvious that by having the disks *e* placed eccentrically, they will enable the vertical bar to rest under the pin-hole when the pin is raised; in other words, they serve as a counter-balance to the lever *f*.

An important feature of my invention consists in having two or more recesses in the rear part of the draw-head, for the purpose of aiding the link in its entrance to another draw-head.

What I claim as my invention, and desire to secure by Letters Patent, is—

The combination, in a draw-head provided with the slot *g* and two or more recesses, *c* *c'*, for the purpose of regulating the position of the link to an approaching draw-head, of the horizontal rod *d*, provided with the eccentrically-placed circular disks *e* and vertical lever *f*, substantially in the manner and for the purposes set-forth.

MATHEW WOODS.
